(57) **CLAIM**

The ornamental design for a display screen or a portion thereof with animated graphical user interface, as shown and described.

DESCRIPTION

FIG. 1 is a front view of a first image in a sequence of a display screen or a portion thereof with animated graphical user interface, showing our new design;

FIG. 2 is a second image thereof;

FIG. 3 is a third image thereof;

FIG. 4 is a front view of a first image in a sequence of the design shown in FIGS. 1 through 3, but disclosed in an alternative environment;

FIG. 5 is a second image thereof; and,

FIG. 6 is a third image thereof.

The outermost broken lines illustrate a display screen or portion thereof and form no part of the claimed design. The remaining broken lines, illustrating portions of the graphical user interface, form no part of the claimed design.

The appearance of the image transitions sequentially between the images shown in FIGS. 1 through 3 and FIGS. 4 through 6. The process or period in which one image transitions to another forms no part of the claimed design.
